CRACKING OF HYDROCARBON OILS

Keith P. Lanneau and Elphege M. Charlet, Baton
Rouge, La., assignors to Standard Oil Develop-
ment Company, a corporation of Delaware

Application August 3, 1950, Serial No. 177,366

4 Claims. (Cl. 196—52)

1

The present invention relates to the conversion of hydrocarbon oils to obtain valuable hydrocarbon products of lower molecular weight. More particularly the invention pertains to an improved process of producing motor fuel range hydrocarbon oils from gas oil range feed stocks containing aromatic constituents, by catalytic cracking. In its broadest aspect, the invention is directed to the catalytic cracking of gas oil range feed stocks of the type mentioned from which aromatic constituents have been removed by a treatment with silica gel.

It is well known in the art that aromatic hydrocarbons are less desirable feed stocks for cracking processes than non-aromatic hydrocarbons, because in cracking aromatic oils more of the feed stock is converted into coke and gas, for a given yield or conversion into gasoline than in cracking non-aromatic feed stocks such as paraffinic or naphthenic oils. In other words, the ratio of gasoline to coke or gas is higher in cracking non-aromatic oils than in cracking aromatic oils, for any given conversion. Excessive coke formation is objectionable in thermal cracking because it reduces the yield of gasoline and causes coking difficulties in the cracking unit. However, such coke formation is particularly harmful in catalytic cracking since the coke formed collects on the surface of the catalyst and reduces its activity. A hydrocarbon oil containing a high percentage of aromatics which are conducive to a low ratio of gasoline to coke is therefore particularly undesirable as a feed stock to catalytic cracking processes.

Prior to the present invention it has been proposed, therefore, to remove the aromatic constituents from the feed stock before it is subjected to cracking. For this purpose, it has been suggested to extract feed stocks containing aromatic constituents with solvents such as phenol, SO_2 , or various chlorinated, nitrated and/or oxygenated hydrocarbons which have a selective solvent power for aromatics, and to use only the raffinate of this extraction as the cracking feed stock. While treatments of this kind afford a

2

substantial improvement with respect to coke formation as well as to gasoline yield based on raffinate it has been found to be necessary to limit the extent of extraction to a partial removal of aromatics in order to prevent excessive amounts of non-aromatic constituents from going into the extract whereby the gasoline yield based on original feed stock would be severely curtailed. In addition the gasoline to coke ratios obtainable in this manner are far from optimum.

It has also been suggested to filter cracking feed stocks through various chars, alumina-containing adsorbents such as bauxite, alumina gel, activated alumina, natural and activated clays, such as fuller's earth, Attapulgus clay, and the like whereby aromatic constituents are removed in addition to other impurities of the feed stock. However, processes of this type likewise suffer from the serious disadvantage that aromatics cannot be completely removed to establish desirable gasoline to coke ratios without greatly reducing the yield of gasoline based on original feed. The present invention eliminates these difficulties.

It is therefore the principal object of the invention to improve the gasoline yield and the gasoline to coke ratio of cracking processes, particularly catalytic cracking processes which are based on feed stocks containing aromatic constituents. Other objects and advantages will appear from the description of the invention given below wherein reference will be made to the accompanying drawing, the single figure of which illustrates schematically a system suitable to carry out a preferred embodiment of the invention.

It has now been found that in cracking and particularly in catalytically cracking feed stocks originally containing aromatic constituents gasoline yields and gasoline to coke ratio may be improved beyond anything attainable by the above-mentioned known processes when aromatic constituents are completely removed from the feed stock by adsorption on silica gel prior to cracking. Actually it has been found that the raffinate ob-

tained by removing the aromatic constituents in this manner gives upon cracking in the presence of catalysts not only a gasoline to coke ratio substantially higher than that obtainable by feed stock extraction with solvents or other solid adsorbents but in addition absolute gasoline yields substantially in excess of those obtainable from the quantity of the original feed from which the raffinate was obtained. The pretreatment of the feed stocks with silica gel may be carried out at temperatures of about 50° to 150° F. and silica gel to feed stock ratios of about 3:1 to 12:1. Any desired pressure may be used.

The highly beneficial effect of the process of the invention will first be illustrated for catalytic cycle oils and partially hydrogenated cycle oils which are particularly undesirable cracking feed stocks as a result of their high aromatics concentrations.

Example I

Separate batches each of a catalytic cycle oil and a hydrogenated cycle oil were subjected to catalytic cracking one batch after pretreatment with silica gel, the other without such treatment.

time is required. Complete removal of non-aromatics was determined by the refractive index of the liquid dripping from the bottom of the vessel. The R. I. of n-heptane is reached when complete separation is effected. The aromatics remaining in the column were removed by desorption with approximately a 2500 cc. wash of acetone. This entire process required only 2½ hours. Use of a cylindrical column properly dimensioned to accommodate this size sample will take 2 or 3 times as long. After the aromatics were desorbed, both the aromatics and non-aromatics were stripped to remove acetone and heptane. On the cycle oil sample the aromatic content was determined to be 44%; and this value was reproducible within 1% and it agreed within 1% with the value determined on a small ASTM adsorption column.

Cracking was carried out in a 200 cc. fixed bed 20 laboratory unit on fresh standard silica-alumina catalyst containing 13% alumina at 975° F. and a feed rate of 1 v./v./hr. in single pass operation with 2 hr. cycle time. The results of these experiments are tabulated below.

TABLE I

	Cycle Oil			Hydrogenated Cycle Oil		
	Total	Aromatic Fraction, 44%	Non-Aromatic Fraction, 56%	Total	Aromatic Fraction, 40%	Non-Aromatic Fraction, 60%
Conversion	43.8	19.0	88.5	51.8	29.4	82.9
Carbon, Wt. Percent	10.7	10.0	5.1	9.7	10.3	5.6
Dry Gas, Wt. Percent	15.9	5.4	31.8	18.6	11.0	28.9
Gas, C. F./Bbl	734	326	1048	858	654	960
Gas Density	0.85	0.65	1.19	0.85	0.66	1.18
D+L	26	6.0	81	36	7.6	77
Naphtha, Vol. Percent	19.8	5.2	58.0	27.1	7.9	57.3
400 E. P. Gasoline, Wt. Percent	15.5	4.8	48.9	21.6	6.0	47.8
Wt. Percent of Total	100.0	44	56	100.0	40.0	60

The feed stocks used had the following inspection:

	Cycle Oil	Hydrogenated Cycle Oil (350 cu. ft. of H ₂ /bbl.)
Gravity, °API	22.2	24.4
Aniline Point	183	174
Bromine No.	14	9
Conradson Carbon, Wt. Percent	0.235	0.100
Carbon, Wt. Percent	88.14	87.85
Hydrogen, Wt. Percent	11.62	12.16
Initial Boiling Pt., °F.	415	349
Final, °F.	898	854

The treatment with silica gel was carried out as follows. The treating vessel was a glass laboratory bell jar of 2 liter volume, 13" long, 5" top diameter tapering to 2½" bottom diameter. This container was packed with a 28-200 mesh silica gel. The oil sample (175 cc. of cycle oil) was diluted with 350 cc. of normal heptane and the mixture was allowed to drip rapidly through a piece of filter paper on top of the silica gel into the vessel. When all the sample was in the gel the non-aromatics were immediately washed from the column with approximately a 2500 cc. charge of normal heptane. No extended contact

50 improvement in yield has been effected by pretreating cycle stock with silica gel for removal of aromatics. For instance, the non-aromatics separated from the feed (column 3) amount to 56% and give a naphtha yield of 48.9%. The naphtha yield then on the basis of the total oil amounts to 27.4% as compared to 15.5% for the actual yield obtained from the total oil. For the hydrogenated product the results are 28.7% for the non-aromatic fraction figured on the basis 55 of the total oil as compared to the 21.6% yield actually obtained from the total oil. In addition to greatly increased gasoline yields, both oils showed marked reduction in carbon formation.

Example II

The results reported in Example I are far superior to the optimum results obtainable by extracting the feed to catalytic cracking processes 70 with selective solvents. The data reported in Table II below compare the results shown in Table I with those obtainable by solvent extraction at extraction and cracking conditions conducive in each case to maximum gasoline production.

TABLE II

Method of Aromatics Removal	Catalytic Cracking Results		
	Wt. Percent 400 E. P. Gasoline	Wt. Percent Carbon	Ratio, Gasoline to Carbon
I. Extraction with Methyl Cellosolve: East Texas Catalytic Cracking Cycle Gas Oil, untreated.....	34.0	4.2	8.1

Non-aromatic fraction thereof from Silica Gel Separation (56% of total oil).....	48.9	5.2	9.6

¹ Volume percent figures.

The above data show that solvent extraction of a catalytic cracking cycle gas oil produced an optimum 50% raffinate which yields upon catalytic cracking a gasoline to carbon ratio 2.7 times higher than the ratio for the unextracted cycle oil. A 2.3-fold improvement in gasoline to coke ratio is obtained on a 79% phenol extracted raffinate from heavy catalytic cycle gas oil and an increase by a factor of 3.2 in the gasoline to coke ratio on the phenol extracted raffinate (80%) from a somewhat heavier catalytic cracking clarified oil. These improvements in the cracking characteristics of the cycle stock feeds by means of selective solvent extraction are not nearly as great as those shown for complete removal of aromatics from cycle stocks by means of separation with silica gel adsorbent. The data above demonstrate that when treating a heavy cycle oil plus clarified oil and entirely removing the aromatic portion, by adsorption on silica gel, a non-aromatic oil is obtained which yields a gasoline to carbon ratio 6.9 times higher than the gasoline to carbon ratio obtained in fixed bed cracking tests on the total oil. This improvement of cycle stock feed resulting from removal of aromatics by silica gel adsorption is more than twice as great as improvements effected with solvent treating.

Other solid adsorbents such as alumina gel, activated alumina, bauxite, fuller's earth, Attapulgus clay, various chars, and natural clays which have been used in filter treatments to remove from oils various undesirable constituents may somewhat reduce the aromatic content of an oil; but the complete selective removal of aromatics as a pretreat for catalytic cracking stocks without reducing gasoline yields based on original oil is not feasible with these other adsorbents.

The above data have dealt with results obtainable by the treatment of such poor cracking stocks as cycle and clarified oils, where aromatic content is high and there is present a large amount of condensed-ring aromatics which are known to be particularly strong carbon formers. Virgin gas oils, the usual feeds to catalytic cracking units, are considerably better cracking stocks since their total as well as their condensed aromatics content is lower. It has been found, however, that cracking of virgin gas oils may likewise be substantially improved by complete selective aromatics removal with silica gel. This is demonstrated in Example III below.

Example III

Extraction and cracking experiments were carried out in the manner described in Example I using a heavy virgin gas oil as the feed stock having the following inspection:

25 Gravity, °API.....	26.4
30 Aniline point.....	203
Bromine No.....	6
Conradson carbon, weight percent.....	0.478
Carbon, weight percent.....	86.98
Hydrogen, weight percent.....	13.00
35 Initial boiling point.....	440
Final, °F.....	1045

This work has shown that complete removal of the aromatic portion from the virgin gas oil feed, by adsorbent extraction on silica gel, yields a non-aromatic fraction of such improved cracking characteristics that equally as good yields of naphtha (figured on the basis of the total, unseparated feed) and lower carbon make are obtained on the non-aromatic fraction alone than from cracking of the total unseparated feed. Data to support this are tabulated below.

TABLE III

50	Total Feed (100% of Total)	Aromatic Frac. (31% of Total)	Non-Aro- matic Fraction (69% of Total)
55 Conversion.....	59.0	42.3	81.1
Carbon, Wt. Percent.....	6.3	10.9	6.0

Wt. Percent on Total Oil.....	31.4	5.0	30.0
60			

Here, as in the case of the cycle oil, an improvement in the gasoline to carbon ratio may be observed when aromatics are extracted from the feed although the total virgin gas oil has been considered heretofore to be an excellent cracking stock as such.

The great significance of this increase in gasoline yield and decrease of the carbon yield on the non-aromatic fraction from either the cycle oil or virgin gas oil (these two oils are conventional cracking feeds) lies in the fact that a silica gel pretreatment for aromatics extraction on either or both virgin gas oil or cycle stock feeds will result in a tremendous increase in gasoline

7 production for the unit, particularly in fluid-type catalytic cracking, since process variables can be changed to permit this.

Most conventional fluid catalytic cracking units are "carbon balance" units; i. e., the capacity for burning carbon off the catalyst limits the conversion permissible. With increased conversion of a given feed to gasoline there is of course an increase in carbon production.

The following is an example of how, in conjunction with a silica gel pretreatment, operating process variables may be changed on a fluid catalytic cracking unit of a given coke-burning capacity to afford approximately a 100% increase in gasoline output, using the heavy virgin gas oil feed mentioned above.

Example IV

The data of Case I below were obtained in an exploratory 68 gm. catalyst, fluid-type catalytic cracking unit at standard test conditions. The data of Case II below are correlations made on the basis of the data of Case I.

TABLE IV

	Case I— Cracking Only	Case II— Silica Gel Extraction and Cracking
Limiting carbon burning capacity, lbs./day.	6	6
Feed to silica gel unit, lbs./day		248
Feed to cracking unit, lbs./day	100	171
Gasoline output, lbs./day	54	105
Conversion, Percent	70	76

The significance of the above cases is as follows. The carbon burning capacity of the unit is 6 lbs. per day. Therefore, the virgin gas oil is fed to the unit at the rate which will give this limiting maximum amount of carbon, which in Case I is 100 lbs. per day, operating at 70% conversion. This type of operation yields 54 lbs. of gasoline.

In Case II the virgin gas oil feed, which is 31% aromatic, is extracted with silica gel, and the non-aromatic stream is fed into the fluid catalytic cracking unit. As in Case I, carbon burning capacity is 6 lbs./day, and the cracking unit will be operated to reach this maximum. Data correlations on the cracking of the non-aromatic feed show that the cracking unit may now be operated at increased feed rates and increased ratio of catalyst to oil feed rates. Specifically in Case II, 248 lbs. per day of the virgin gas oil feed may be charged to the extraction unit, providing 77 lbs. per day of aromatic extract and a feed rate of 171 lbs. per day into the cracking unit, where conversion may be maintained at 76% without yielding more than the permissible maximum 6 lbs. of carbon. For these new operating conditions, made possible by this invention, the gasoline output becomes 105 lbs. per day. The increase in gasoline output per unit time is therefore approximately 100%. The significance of the data of Cases I and II lies in their relative values which will be substantially the same in operation on a commercial scale.

In conventional fluid cracking units the total feed is a mixture of fresh gas oil and cycle gas oil. Gas-oil recycle is necessary because of the large make of such cycle oil. As indicated above the carbon produced in catalytic cracking units chiefly comes from highly condensed aromatics formed during recycling operation. The im-

proved feed conditions resulting from silica gel treatment, permit single pass operation without gas oil recycle, so that the production of highly condensed carbon forming aromatics may be eliminated. It should be pointed out that even when feeding 100% non-aromatics, aromatics will be formed in the cracking operation. Upon recycling, these aromatics further condense and eventually go to coke or carbon on the catalyst.

10 The gas oil produced in single pass operation, containing no or very little condensed aromatics may be fed to thermal cracking units for further gasoline yields or used for any other desired purpose. The smaller amount of cycle oil formed, when the feed is pretreated with silica gel, renders such thermal cracking or other disposal of catalytic gas oil stocks in place or recycling much more attractive than heretofore and this type of operation is a preferred embodiment of the invention.

In describing the silica gel extraction procedure used in Example I it has been pointed out that the tapered contacting vessel employed affords advantages as compared to conventional 25 contacting vessels of cylindrical shape. It has been found that a 6 liter bell jar, 18" long, 8" top diameter and tapering to 3" bottom diameter works equally as well and accommodates three times as much oil. By comparison, a 2" diameter cylindrical column holding 6 liters of adsorbent would have to be 10 ft. long, requiring longer percolation times and even application of pressure to facilitate percolation at a feasible rate. If the length of the cylindrical column is reduced to 30 shorten the percolation times or if the diameter is increased to accommodate larger amounts of silica gel in large scale operation, there is a strong tendency for the oils to "channel" in the column, and no clean cut separation can be effected. It is generally accepted that the length to diameter ratio of a silica gel adsorption column should be about 30:1 and never less than 35 15:1. Thus, very high columns which are inconvenient and slow in percolation have been required heretofore in conventional large-scale 40 operation. The column design used in carrying out the experiments described herein offers substantial advantages in this respect as pointed out above. In general, these advantages may be secured by employing tapered silica gel columns of 45 circular cross sections having a ratio of length: top diameter: bottom diameter of the order of 13:5:2.5. A suitable manner of applying silica gel columns of this type in practical operation is 50 illustrated in the drawing.

55 Referring now to the drawing, there are shown therein three tapered columns 1, 2 and 3 of the type specified above. Columns 1, 2 and 3 are used in a cyclic type of operation involving three 60 cycles, namely (A) charging of the feed and adsorption of the aromatics; (B) washing-out of the non-aromatic raffinate with low boiling paraffin hydrocarbons, combined with stripping of the hydrocarbon solvent from the raffinate and passage of the stripped raffinate to the cracking 65 unit; and (C) desorption of the aromatics from the gel and regeneration of the latter by means of steam followed by drying of the gel with hot air. Each column is used successively to carry out cycles A, B and C in the order named, operation of the three columns being properly staggered to provide a continuous flow of treated feed stock to the cracking plant. Columns 1, 2 and 3 are drawn so that each will illustrate one of the three cycles, column 1 illustrating cycle A, col-

umn 2 illustrating cycle B and column 3 illustrating cycle C. Actually, however, columns 1, 2 and 3 are of identical design.

In operation the gas oil feed such as virgin gas oil, cycle oil, or heavier feed stocks may be supplied at atmospheric pressure through line 5 to the top of column 1 in an amount of about $\frac{1}{3}$ to $\frac{1}{2}$ lbs. per lb. of silica gel in the column depending on concentration of aromatics in the feed. The oil enters the silica gel preferably through a suitable distributing means such as a spray nozzle or a perforated grid 7 as shown in the drawing to assure even distribution of the feed over the cross-sectional area of the column. The charge may be allowed to flow into column 1 at atmospheric pressure and temperature. This completes cycle A.

In the next cycle the column is operated as shown in connection with column 2. A low boiling normally liquid paraffinic hydrocarbon such as pentane, hexane, heptane, etc., may be supplied from tank 9 through line 11 and grid 7 to the silica gel at atmospheric temperature and pressure in an amount of about 3 to 16 lbs. per lb. of gas oil feed originally charged. The wash oil removes the non-aromatic fraction from the silica gel while the aromatics remain on the adsorbent. The wash oil extract may be withdrawn via line 13 and collected in a stripper 15 wherein the wash oil is stripped off the non-aromatic fraction with hot air or steam introduced through line 16 to be returned via line 17 to tank 9 for reuse. There is a continuous circulation of wash oil until extraction is completed. The non-aromatic fraction may be passed via line 19 directly to a fluid type catalytic cracking unit schematically identified at 21. This unit may be operated at conventional conditions except that in accordance with a preferred embodiment of this invention the feed rate may be increased by about 50 to 100% and no gas oil recycle is employed. When all of the non-aromatic fraction is removed from the silica gel as determined by continuous refractive index measurements on the stream in line 13 operation is switched to cycle C.

In cycle C, as illustrated by column 3, steam may be introduced through line 23 at a temperature of about 212° to 500° F. to desorb the aromatics and regenerate the silica gel. The desorbate withdrawn through line 25 may be stripped of residual wash oil in stripper 26 with hot air injected through line 27, cooled in cooler 28 and passed to settler 29 from which aromatic by-product may be recovered via line 31 and water may be withdrawn via line 33. Wash oil is returned to tank 9 through line 35. After sufficient steam to regenerate the gel has been so employed at the conditions specified the silica gel may be dried by introducing air via line 23 at a temperature of about 100° to 300° F. until condensation of water in cooler 27 ceases. Thereafter the column is ready for a fresh charge of oil feed.

In place of the batch type operation of the adsorption system illustrated in the drawing continuous operation may be employed involving continuous circulation of the silica gel successively through an adsorption tower, a wash tower, a regeneration tower, a drying tower, and back to the adsorption tower as will be understood by those skilled in the art. However, a higher adsorption and separation efficiency may be obtained in a system of the type illustrated by the drawing.

Fluid catalytic cracking has been repeatedly referred to in the above description as the preferred cracking operation for the purposes of the invention. While the design and operation of such fluid catalytic cracking systems are widely known in the art it is noted for the sake of completeness that they involve the use of finely divided catalysts such as various activated clays or composites of silica gel with alumina, magnesia and/or boria, having particle sizes of about 50-400 mesh. The catalyst is maintained in separate cracking and regenerating vessels in a dense turbulent fluidized state by gaseous media passing upwardly through the beds at linear superficial velocities of about 0.3-5 ft. per sec. The catalyst circulates continuously between the reactor and regenerator, heat for cracking being generated by burning carbon from the catalyst in the regenerator. Conventional conditions include cracking temperatures of about 800-1000° F., regenerator temperatures of about 950-1200° F. but higher than the cracking temperature employed, pressures of from subatmospheric to 500 p. s. i. g. or higher, total oil feed rates of about 4 to 5 w./hr./w. catalyst/oil ratios of about 6:1 to 10:1 and oil recycle to fresh feed ratios of about 0.5-5 on a weight basis. When employed in the present invention the oil feed rate may be increased to about 6 to 10 w./hr./w. at a recycle ratio of 0 and a catalyst/oil ratio of about 11:1 to 17:1, but otherwise conventional conditions. While operations of this type are preferred for the purposes of the invention, marked improvements may also be secured when fixed bed, moving bed or suspensoid systems are used. The gasoline yields and the gasoline to carbon ratio may likewise be improved when employing thermal cracking in the cracking stage of the invention. The silica gel extraction of cracking stocks in accordance with the invention not only reduces carbon forming tendencies by aromatics removal, but it prevents catalyst contamination by removal of nitrogen, oxygen and sulfur compounds and removal of ash contents such as metallic salts from the oil. Moreover, the aromatic extract is of unusual nature. This pure concentrate of high boiling aromatic oils is a valuable source of chemicals for such by-products of the oil industry as carbon black, plasticizers, detergents, weed killers, wood preservatives, solvents, and others.

The foregoing description and exemplary operations have served to illustrate specific embodiments of the invention but are not intended to be limiting in scope.

What is claimed is:

1. The process of cracking hydrocarbon oils which comprises contacting in a contacting zone a gas oil range hydrocarbon oil boiling above the motor fuel range, having a final boiling point not exceeding 1045° F. at atmospheric pressure and containing aromatic constituents, with silica gel in proportions adequate to adsorb said aromatic constituents substantially completely on said silica gel, recovering an oil substantially free of aromatics from said contacting zone and catalytically cracking the oil so recovered in the absence of said aromatic constituents at conditions conducive to the formation of motor fuel range hydrocarbons.

2. The process of claim 1 in which said cracking is carried out in the presence of a dense turbulent fluidized mass of sub-divided cracking catalyst.

3. The process of cracking hydrocarbon oils which comprises contacting in a contacting zone a hydrocarbon oil boiling within the gas oil range, having a final boiling point not exceeding 1045° F. at atmospheric pressure and containing aromatic constituents with silica gel in proportions adequate to adsorb said aromatic constituents substantially completely on said silica gel, recovering an oil substantially free of aromatics from said contacting zone, passing the oil so recovered to a system comprising a cracking zone and a product fractionation zone, cracking said recovered oil in said cracking zone at cracking conditions in the presence of a dense turbulent fluidized mass of sub-divided cracking catalyst and in the absence of said aromatic constituents, withdrawing cracked products from said cracking zone, separating said products in said fractionation zone into motor fuel and heavier fractions and withdrawing all of said fractions from said system, so as to operate at a recycle ratio of zero.

4. The process of claim 3 in which said cracking conditions include oil feed rates of about 6-10 lbs. of oil per hour per lb. of catalyst in said cracking zone and catalyst to oil feed ratios of about 11:1 to 17:1 by weight.
